UNITED STATES PATENT OFFICE

BERNHARD G. KUHNE, OF AKRON, OHIO

ABRADING, BUFFING, OR POLISHING DRUM

Application filed February 25, 1929. Serial No. 342,391.

This invention relates to abrading, buffing or polishing drums on which a cylinder of abrasive buffing or polishing material such as emery cloth is mounted.

The general purposes of the invention are to provide as an abrading or like drum an expandible drum adapted to receive an endless cylinder of abrasive or like material about the same while collapsed preferably with a 10 pad of yielding material between the drum and cylinder and adapted to be expanded to effectively secure the material smoothly and tightly on the drum surface, and also to provide a drum including pivoted sections and 15 expanding means so balanced and the drum sections so held together that the drum will revolve truly at all operating speeds, whereby a uniform abrading or polishing action is secured and the material wears even or uniformly over its entire surface.

The foregoing and other purposes are attained in the abrading or polishing drum construction illustrated in the accompanying drawing and described below. It is to be 25 understood that the invention is not limited to the specific form thereof shown and described.

Of the accompanying drawing,

Figure 1 is an end elevation of a drum embodying the invention; and

Figure 2 is a diametral section on line 2—2 of Figure 1.

Referring to the drawing, the drum comprises a plurality of sections 10, 10 mounted 35 on a central hub 11 which may be secured upon a drive shaft (not shown). The hub 11 is provided with outwardly projecting apertured lugs or eyes 12, 12 upon which the sections 10 are pivoted by means of shafts 13, 13 extended through said lugs 12 and through 40 inwardly extended apertured lugs or eyes 14, 14 on drum sections 10. The lugs 14 preferably are positioned between lugs 12, the cooperating lugs 12 and 14 preferably bearing 45 against each other and the apertures thereof being provided with elongated bushings 15, 15 extending through each pair of cooperating lugs 12 and 14 about shafts 13, the shafts 13 preferably being eccentrically mounted in 50 the bushing. The cooperating lugs and

shafts are so placed to counterbalance each other in the drum construction.

The free ends of each drum section 10 are provided with inwardly projecting hooks 16 arranged to engage with corresponding outwardly extending hooks 17 on hub 11, the hooks being undercut as shown so that centrifugal force developed by rotation of the drums tends to hold the hooks in engagement.

The drum expanding devices comprise eccentrics 18, 18 on shafts 13 cooperating with the outer ends of outwardly projecting lugs 19, 19 on hub 11 and with the rear faces 20 of the hooks 16 to expand the drum, the eccentrics being self-locking between said faces to hold the drum expanded.

The drum sections are of such length that sufficient spaces may be provided as at 21, 21 to permit the required contraction of the drum and plates 22 are secured to each section so as to overlie the spaces 21 and complete the periphery of the drum.

The abrading or polishing material in the form of an endless cylinder 23, either of flexible or stiff material, is slipped onto the drum while collapsed, a resilient pad 24 of felt, rubber or the like preferably being first mounted on the drum. The drum is then expanded to the condition shown in the drawings and is ready for use. The drum parts being balanced as shown and centrifugal force serving in addition to the expanding eccentrics to hold the drum parts expanded in true circular form, the drum runs true and the abrading or polishing action is uniform.

It will appear from the foregoing that a simple, effective abrading or polishing drum has been provided. It will be understood that this drum can be employed for abrading or polishing metal, wood and other surfaces. Obviously modifications of the invention may be resorted to without departing from the spirit thereof or the scope of the appended claims.

What is claimed is:—

1. An expandible abrading or polishing drum construction comprising a hub, drum sections pivoted on the hub, the pivots for the sections including shafts, the sections be-

- ing arranged so that the free end of one section is adjacent the pivoted end of another section, interengaging hook means on the hub and the free ends of the sections, said hook means being adapted to be held in engagement by centrifugal force when the drum is rotated, and means for expanding the drum comprising eccentrics on said shafts, adapted to cooperate with the outer faces of lugs on the hub and with the rear faces of the hooks on the drum sections to lock the drum in expanded condition, the sections, pivots, hooks and the drum expanding means being disposed at diametrically opposite points so as to counterbalance each other.
2. An expansible abrading or polishing drum construction comprising a hub, drum sections pivoted on the hub, the pivots for the sections including shafts, the sections being arranged so that the free end of one section is adjacent the pivoted end of another section, interengaging hook means on the hub and the free ends of the sections, said hook means being adapted to be held in engagement by centrifugal force when the drum is rotated, and means for expanding the drum comprising eccentrics on said shafts adapted to cooperate with the outer faces of lugs on the hub and with the rear faces of the hooks on the drum sections to lock the drum in expanded condition.
3. An expansible abrading or polishing drum construction comprising a hub, drum sections pivoted on the hub, the pivots for the sections including shafts, the sections being arranged so that the free end of one section is adjacent the pivoted end of another section, interengaging hook means on the hub and the free ends of the sections, said hook means being adapted to be held in engagement by centrifugal force when the drum is rotated, and means for expanding the drum comprising eccentrics on said shafts adapted to cooperate with the free end of the drum sections to lock the drum in expanded condition, the sections, pivots, hooks and the drum expanding means being disposed at diametrically opposite points so as to counterbalance each other.
4. An expansible abrading or polishing drum construction comprising a hub, drum sections pivoted on the hub, the pivots for the sections including shafts, the sections being arranged so that the free end of one section is adjacent the pivoted end of another section, interengaging hook means on the hub and the free ends of the sections, said hook means being adapted to be held in engagement by centrifugal force when the drum is rotated, and means for expanding the drum comprising eccentrics on said shafts adapted to cooperate with the free end of the drum sections to lock the drum in expanded condition.
5. An expansible abrading or polishing

drum construction comprising a hub, drum sections constituting the entire outer surface of a drum pivoted on the hub, the sections being arranged so that the free end of one section is adjacent the pivoted end of another section, interengaging hook means on the hub and the free ends of the sections, said hook means being adapted to be held in engagement by centrifugal force when the drum is rotated, and means for expanding the drum.
